UNITED STATES PATENT OFFICE.

THEODORE W. FRECH, JR., AND JOHN T. FAGAN, OF CLEVELAND, OHIO, ASSIGNEES TO
GENERAL ELECTRIC COMPANY, A CORPORATION OF NEW YORK.

FILAMENT-SUPPORT-WIRE-INSERTING MACHINE.

1,220,836.

Specification of Letters Patent. Patented Mar. 27, 1917.

Application filed October 1, 1913. Serial No. 792,900.

To all whom it may concern:

Be it known that we, THEODORE W. FRECH, Jr., and JOHN T. FAGAN, citizens of the United States, residing at Cleveland, county 5 of Cuyahoga, State of Ohio, have invented certain new and useful Improvements in Filament-Support-Wire-Inserting Machines, of which the following is a specification.

Our invention relates to machines used in 10 the manufacture of incandescent lamps and, more particularly, to machines for inserting hooked wires in glass rods so as to produce the filament supports commonly used in connection with metallic filament incandescent 15 lamps. The object of our invention is to produce a machine of the aforesaid character by means of which the necessary operations may be quickly and accurately performed.

According to our invention, means are 20 provided for holding a glass rod which commonly has buttons formed thereon into which the support wires are to be inserted, so that it may be turned by the operator to receive as many support wires as desired. The machine is provided with wire holding 25 means and with a wire feeding means comprising a guide having a gripping means located so that the wire may be firmly seized 30 and inserted into the glass button upon the proper action by the operator. Moreover, means are provided for fusing that portion of the button which is to receive a wire, and a cooling means is provided which is brought 35 into action immediately after the insertion of the wire to cause the rapid solidification of the glass around the end of the said wire. The glass fusing means comprises means for directing a flame against a portion of the 40 edge of the button on the glass rod and the said means is angularly disposed relative to the plane of the said button so that there is no danger of injuring wires previously inserted in the button. Our machine comprises 45 also a wire cutting and hook forming means which are brought into operation after the withdrawal of the wire gripping means. This means practically simultaneously cuts off the wire and forms the hook at the end 50 thereof. The cutting means is made adjustable so that sharp edges may be readily substituted for those dulled by the wire. This is of decided advantage, because the thin tungsten or other wire of the resilient

supports, for the insertion of which our machine is particularly adapted, very quickly dulls the ordinary cutter. To this end, the cutters are disk-shaped and have serrated edges. This structure has the additional advantage that the wire is alined accurately 60 by the cutter teeth at each cutting operation. The parts of our machine are adjustable so that various sizes of glass rods and wire may be handled thereby. Moreover, the support for the glass rod is such that 65 the support wires may be inserted at any desired angle therewith. The parts of the machine are so arranged and connected that they are actuated by manipulating a handle or similar device to automatically perform the aforesated operations in proper sequence. Various other advantages of our machine will appear from the more detailed 70 description which follows.

Our invention will be more clearly understood by referring to the accompanying drawing in which Figure 1 is a front elevation of the machine; Fig. 2 is a plan; Fig. 3 is a detail section on the line 3-3 of Fig. 2; Fig. 4 is a transverse vertical section 80 showing a portion of the operating shaft and connected parts; Fig. 5 is a sectional elevation of a part of the machine showing the air valve controlling means; Figs. 6 and 7 are detail elevational views showing the 85 hook forming and cutting dies in open and closed position respectively; and Figs. 8 and 9 are detail elevations showing the wire inserting mechanism in advanced and retracted position respectively. 90

Referring to Figs. 1 and 2, it will be seen that the machine comprises a base 10 which may be secured in any suitable manner to the top of a work bench. At one end, as shown, to the left of Figs. 1 and 2 is an adjustable support for the rod 11 into button 12 of which the supports are to be inserted. The said support consists of a spring clamp 13 consisting of two members, one of which, 14, is stationary, is secured to the horizontally extending rod 15 and has angularly disposed bearing surfaces 16 at its end. The other member 17 is slidably fastened to the rear of the member 14, being held thereto by the bolt and nut 18 passing through slot 19 in said member 17. The member 17 is provided at the end thereof with hooks 20 which are adapted to conform to the sur-

face of the glass rod 11 and to hold the same firmly against the surfaces 16, being acted upon by a spring 21 which extends from pin 22 therein to the pin 23 extending from rod 15. By means of the vertical rod 24 pivotally mounted in the holding member 13 and carrying a lug 25 which extends through a slot in member 17, and the handle 26, the said member 17 may be advanced to allow the insertion or removal of the glass rod 11. To allow the position of the holding clamp to be readily adjusted, the rod 15 is adjustably held in the sleeve 27 and the said sleeve is pivotally supported by standard 28 carrying sleeve 29 having ears 30 through which extend the adjusting screws 31. The standard 28 is mounted to allow adjustment in a sleeve 32 carrying clamps 33. To allow the accurate positioning of glass rods in the clamping device, a stop 34 may be adjustably mounted on the stationary member 14 of the spring clamp, and in inserting the glass rod into the clamp the top surface of the button 12 should be forced against the said stop. In order that the operator may know accurately how far to turn the glass rod after the insertion of a support, an indicating pointer 35 adjustably held by a standard 36 may be provided.

At the other end of the base 10 is provided a holder for the wire holding means or reel 37 carrying the support wire 38. The said holder consists of a horizontally extending rod 39 carrying the stationary bearing 40 and the movable bearing 41 which is acted upon by spring 42 adjustably held by bushing 43. The wire 38 extends from the reel 37 through the channel 44 in a reciprocating guide 45 which slides in the uppermost slot 46 in a carrier 47 which is supported by the hollow vertical frame member 48. As shown in Figs. 5, 8 and 9, the forward end of the guide 45 is transversely channeled at 49 to receive the end of the gripper 50 which is pivoted thereto at 51. The said gripper is offset somewhat back of its forward end at 52 (see Fig. 2) and has an oblique shoulder 53 in line with its gripping end. Arranged and adapted to engage the said shoulder 53 is the end of an oblique arm 54 which is parallel to the shoulder 53. The arm 54 is attached by a vertical arm 55 to the bar 56 which is reciprocatably mounted in a slot 57 in the carrier 47. A spring 58 normally holds the gripper against the wire in the channel. The bar 56 extends through the carrier somewhat beyond the rear end of bar 45 and is attached to a vertically extending member 59. This member has an upper shoulder 59' in line with bar 45. Also attached to the member 59 is the horizontally extending bar 60 which is slidably mounted in the lowermost slot 61 in the carrier 47, and extends to about the middle of the hol-

low frame support 48. Pivotally attached

to the forward end thereof and slotted to receive the same is the crank 62 attached to the operating shaft 63 which is provided with handle 64. A spring 65 extends from the lower end of the member 59 to an adjustably held supporting arm 66 mounted upon the rear framework of the apparatus. The uppermost bar 45 has formed therein at a point somewhat beyond the front end of slot 46 a shoulder 45' and the vertical arm 55 is normally held against the said shoulder through the action of spring 65 on the bar 56.

The above described parts are proportioned and arranged so that when the operating shaft is turned to the left by means of handle 64 the member 59 is moved forward with its connected parts against the action of spring 65. The forward reciprocation of bar 56 causes the end of arm 54 to bear against the shoulder 53 thus forcing the gripper 50 down upon the wire. The continuation of the reciprocation causes the shoulder 59' to engage the end of the upper bar 45 and the wire is advanced with the parts in the position shown in Fig. 8 to insert the end thereof into the glass button 12. Just prior to the insertion of the wires, as hereinafter described, a gas blow flame is played upon the part of the button which is to receive the support wire and immediately following the insertion, as hereinafter described, a cooling air blast is played upon the said button part to solidify the same. Upon the release of pressure upon the handle 64 the action of the spring 65 causes the bar 56 to be retracted thus releasing the pressure upon the gripper 50 and further causes the arm 55 to engage the shoulder 45' on bar 45 and to carry that bar with the gripper 50 back to its original position. At the same time the operating handle 64 is brought to vertical position.

The flame for fusing that portion of the button 12 which is to receive the support wire is directed from the air and gas burner 67. This is of the character disclosed in Fagan Patent No. 1,031,842, issued July 9, 1912, and comprises the trough-shaped head 68 covered by gauze 69 and communicating with a gas supply pipe 70. The air blow pipe 71 is arranged to direct a blast of air longitudinally of the trough and to direct a pointed blue gas flame against the button 12. The blow pipe is connected as by the goose neck 72 to the air supply pipe 73. As shown in Fig. 3, the gas pipe 70 is connected to a passage 74 in a member 75 and said passage communicates with a valve chamber 76, the passage 77 of which is controlled by the adjustable valve 78. A pipe 79 communicates with the passage 77 and serves as a support for the burner as a whole, being, as shown in Figs. 1 and 2, held by the clamp 80 which is held between grooved clamping members 81 by the screw clamp 130.

82. This connection permits the universal adjustment of the burner; the air pipe 73 and the inlet passage 83 connecting thereto being controlled by adjustable valve 85. The 5 pipe 86 communicating with the inlet passage 84 is connected to a rubber or other flexible supply tube 87. Means are provided for checking the air supply to the blow pipe 71 after the glass button has been softened 10 sufficiently to allow the insertion of the support wire. As shown, this means comprises a clamp 88, between the short stationary part 89, and the longer movable part 90 of which, the flexible tube 87 passes. The part 15 90 is pivoted at 91 to the frame member 48 and works between the guide pins 92. Projecting from the same face thereof which engages the tube 87 and at the opposite end thereof is a lug 93 which bears against the 20 cam 94 upon the operating shaft 63. The said cam has an indentation 95 therein which corresponds to the position at which the blow flame is to be directed against the button 12. When this reaches the lug 93 the 25 pressure is released upon the tube 87. At all other positions of the operating handle the tube 87 is firmly compressed between the members of the clamp and the air blast is shut off. The movement of the operating 30 handle to the left is limited by the engagement of a pin 95' projecting from collar 95" on shaft 63 with the top of the clamp-member 90.

As stated heretofore, means are provided 35 whereby a blast of cooling air is directed against that portion of the button 12 which receives the support wire immediately upon the insertion of the said wire. The cooling blast is directed by means of the blow pipe 40 96 which is connected to the union 97 secured to the standard 48. As shown in Fig. 5, the pipe 96 communicates with the passage 98 in the said union. Controlling the inlet end 45 of the said passage is a valve 99 which is adapted to slide in the cylinder 100 against the action of spring 101. Communicating with the said cylinder is a supply pipe 102 which, as shown in Fig. 1, communicates with an air reservoir 103. To the opposite 50 end of the cylinder 100 an outlet pipe 104 communicates. This pipe connects with a pressure accumulating device not shown, the purpose of which is to permit the blast to be quickly turned on. The inlet to the pipe 104 55 is controlled by valve 105 mounted upon the same stem 106 as the valve 99. The said valves are so disposed that when one is in open position the other is closed. The stem 106 extends somewhat beyond the end of 60 cylinder 100 and the end thereof is adapted to be engaged at the proper time by the end of a pin 107 adjustably mounted on an offset arm 108 extending from the member 59. The arrangement is such that as the member 65 59 completes its forward movement and as

the support wire enters the glass button, the valve 105 is moved to close outlet 104 and valve 99 to open inlet passage 98 and to allow a cooling blast to be directed upon the button.

70 After the gripper 50 has been withdrawn to its initial position as shown in Fig. 9, the final step is to form the hook upon the inserted support wire and to cut the same from the rest of the wire. This hook former and 75 cutter is illustrated in detail in Figs. 6 and 7. It comprises upper and lower members mounted on shafts 109 and 110 respectively. The upper member comprises the cutter 111 and the male die member 112. The cutter 80 111 is preferably disk-shaped, has a serrated edge and is rotatably mounted on an arm 113 extending from the journal 114 mounted on the shaft 109. The die member 112 is removably held to the arm 113 by the clamp 85 115. The lower member of the device consists of the arm 116 journaled loosely on shaft 110, the female member 117 of the die being clamped removably thereto and the serrated cutting disk 117' being mounted thereon so that it may be adjusted by rotation thereof. One advantage of the rotatably-mounted serrated-edged disk cutters is that when one pair of edges becomes dull, a sharp pair may be brought into operation. 90 Moreover, the teeth of the cutters act to hold the wire in proper position when cut. One of the shafts, as shown, shaft 109, has attached thereto a means for turning the same. The journals of the arms 113 and 116 are 95 provided with intermeshing teeth 118 so that the rotation of the shaft 109 in one direction causes the cutter and die members to approach each other and in the other direction to separate a proper distance to allow the 100 passage of the gripper in the next operation of the machine. The shaft 109 extends through and is journaled near one end in a supporting bracket 119, which is slidably 105 mounted on an arm 120 extending from the frame 48, being held in any desired position by the set screw 121. The other end of the shaft is journaled in stationary bracket 122 extending from the head 47. An adjusting 110 screw-threaded pin 123 extends through correspondingly screw-threaded holes in the stationary bracket, and in the lug 124 extending from the movable bracket 119. By loosening the set screw 121 and turning the screw pin 123 in the proper direction, the 115 position of the cutter and die may be accurately adjusted. The shaft 109 is square in section at the end thereof remote from the cutter and die and passes through a square hole in a crank 125 which is pivotally attached to a vertically extending pin 126. The latter extends loosely through a hole in a guide bracket 127 which extends from the journal of the operating shaft 63. A lug 128 120 projecting from a sleeve fast to the shaft 125 125 130

63 is adapted to engage the end of the pin 126 when the operating handle is turned to the right and to raise the said pin to turn the shaft 109 in such a direction that the cutting and die members are brought together. The bracket 127 acts as a stop to limit the movement of the operating shaft when the lug 128 comes in contact therewith. A strong spring 129 attached to the framework 10 of the machine at the one end and to an apertured arm 130 extending from the outer end of crank 125 serves to return the shaft 109 and connected parts to their original positions as the handle 65 is turned to the right. 15 The spring 131 acting against the collar 132 on shaft 109 serves to hold the same yielding against lateral displacement relative to bracket 119.

It will be apparent from the above description that the operations of heating the button, inserting the end of the wire into the button, cooling the button and withdrawing the wire gripper are successively performed during the movement of the operating lever from vertical position to the left until the stop pin 95' engages the top of clamp 90 and then back to vertical position. Movement of the operating lever to the right then causes the lug 128 to engage 25 end of rod 126 which by turning shaft 109 causes the cutter and hook forming members to come together. This results in the severance of the inserted support wire and the formation of a hook at the end thereof. 30 Upon subsequent movement of the operating lever to the left the cutter and die members are automatically separated through the action of spring 129. The operator may then turn the glass rod until it is in position for 35 the insertion of another support wire. Upon the insertion of the proper number of support wires in the button of one rod, the rod may be readily removed by a lateral movement thereof after release of the spring 40 clamp 13. 45

What we claim as new and desire to secure by Letters Patent of the United States, is:—

1. A machine of the character described comprising means for holding a rod and indexing the same around to receive a ring of wire supports, a wire holder, means for advancing said wire after each indexing operation and inserting an end thereof into the said rod and means for directing a flame 50 to fuse the edge of said button at the point of insertion of each wire support, said flame directing means being disposed at an angle with the plane of insertion of said supports to avoid impairing supports already 55 inserted.

2. A machine of the character described comprising means for holding a rod with a button formed thereon so that the said button is more nearly horizontally than vertically disposed and for indexing said rod 60

around its longitudinal axis to receive a series of wire supports on the periphery of said button, a wire holding means, means for advancing said wire after each indexing operation and inserting an end thereof into 70 the edge of the said button and means for directing a flame against the edge of said button to fuse a portion thereof, said flame directing means being angularly disposed with relation to the plane of the aforesaid button 75 to avoid impairing supports already inserted.

3. A machine of the character described comprising means for removably holding a rod, a wire holding means, means for directing a flame so as to fuse a portion of said rod, means for gripping and advancing said wire so as to insert an end thereof into the fused portion of said rod, means for directing a cooling blast against said fused portion 85 and means whereby the aforesaid means are successively operated.

4. A machine of the character described comprising means for removably holding a rod, a wire holding means, means for directing a flame so as to fuse a portion of said rod, means for gripping and advancing said wire so as to insert an end thereof into the fused portion of said rod, means for directing a cooling blast against said fused portion 90 95, an operating shaft and means intermediate said shaft and the aforesaid means whereby the actuation of said shaft causes the said means to operate successively.

5. In a machine of the character described, means for holding a glass rod, a wire holding means, a reciprocatable gripping means arranged to insert an end of said wire to said rod, means brought into operation immediately prior to the insertion of said wire for fusing the portion of the said rod to receive the same and means brought into operation immediately following said insertion for directing a short cooling blast against said portion.

6. A machine of the character described comprising means for holding a rod or other article, means for directing a flame against a portion of said article, a reciprocatable wire gripping means, a wire cutting means, an oscillatable operating shaft and means connecting said shaft and the aforesaid means whereby said shaft may be oscillated back and forth to bring the said means successively into operation.

7. A machine of the character described comprising means for holding a rod or other article, and indexing the same around to receive a series of wire supports, means for directing a flame against a portion of said article, a reciprocatable wire gripping means, a wire cutting and hook forming means, an oscillatable operating shaft and means connecting said shaft and the aforesaid means whereby said shaft may be 115 120 125 130

- oscillated back and forth after each indexing operation to bring the said means successively into operation.
8. A machine of the character described comprising means for removably holding a glass rod, means for directing a flame against a portion thereof to fuse the same, a wire holding means, means for gripping and advancing said wire so as to insert an end thereof into said fused portion of said rod, a cutting and hook forming means, an operating shaft, and means whereby the rotation of said shaft in one direction causes said fusing and wire inserting means to operate.
9. A machine for mounting wire supports on incandescent lamp stems, comprising an adjustable stem holder; means for directing a heating flame against a portion of the stem to fuse the same; a wire feeding means for gripping and advancing said wire so as to insert an end thereof into the fused portion of said stem; a cutting and forming device; an oscillatable operating shaft and connections whereby the oscillation of said shaft in one direction causes said fusing and wire feeding means to operate successively and other connections whereby the oscillation of said shaft in the opposite direction causes said cutting and forming device to operate.
10. A machine for mounting wire supports on incandescent lamp stems, comprising a stem holder; means for directing a heating flame against a portion of the stem to fuse the same; a reciprocable wire feeding device for gripping and advancing said
- wire so as to insert an end thereof into the fused portion of said stem; a cutting and forming device for detaching and forming a hook on an end of the wire supports; an oscillatable operating shaft normally maintained in a neutral position, and mechanical connections between said shaft and said fusing and wire inserting devices whereby the rotation of said shaft in one direction causes these devices to operate successively and other connections whereby the rotation of said shaft in the opposite direction causes said cutting and forming devices to operate.
11. A machine for mounting wire supports on incandescent lamp stems, comprising a stem holder; means for directing a heating flame against the stem to fuse the same; a wire feeding means for gripping and advancing said wire so as to insert the same into the fused portion of said stem; means for chilling the fused portion of said stem after the insertion of the wire; a cutting and hook forming means; an operating shaft and mechanical connections whereby rotation of said shaft in one direction causes said fusing, wire inserting and chilling devices to operate successively and other connections whereby the rotation of said shaft in the opposite direction causes said cutting and hook forming devices to operate.

In witness whereof, we have hereunto set our hands this 29th day of September, 1913.

THEODORE W. FRECH, JR.
JOHN T. FAGAN.

Jos. E. KEWLEY.

It is hereby certified that in Letters Patent No. 1,220,836, granted March 27, 1917, upon the application of Theodore W. Frech, Jr., and John T. Fagan, of Cleveland, Ohio, for an improvement in "Filament-Support-Wire-Inserting Machines," errors appear in the printed specification requiring correction as follows: Page 4, line 54, claim 1, strike out the word "said"; same page and claim, line 55, for the words "the edge of said button" read *said rod*; and that the said Letters Patent should be read with these corrections therein that the same may conform to the record of the case in the Patent Office.

Signed and sealed this 24th day of April, A. D., 1917.

[SEAL.]

F. W. H. CLAY,
Acting Commissioner of Patents.
